(57) **CLAIM**

The ornamental design for a control module, as shown and described.

DESCRIPTION

FIG. 1 is a perspective view of a control module showing my new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The broken lines and de-emphasis in the figures are used to represent portions of the control module that form no part of the claimed design.
